UNITED STATES PATENT OFFICE.

ROBERT E. KEMPER, OF RENSSELAER, NEW YORK.

SHEET-FEEDING MACHINE.

1,387,494.

Specification of Letters Patent. Patented Aug. 16, 1921.

Application filed November 18, 1920. Serial No. 424,851.

To all whom it may concern:

Be it known that I, ROBERT E. KEMPER, a citizen of the United States, residing at Rensselaer, in the county of Rensselaer and 5 State of New York, have invented certain new and useful Improvements in Sheet-Feeding Machines; and I do hereby declare the following to be a full, clear, and exact description of the invention, such as will 10 enable others skilled in the art to which it appertains to make and use the same.

My invention consists in the novel features hereinafter described, reference being had to the accompanying drawings, which 15 represent one embodiment of the invention selected by me for the purpose of illustrating the same, and the said invention is fully disclosed in the following description and claims.

20 The object of my invention is to provide mechanism for automatically feeding in rapid succession, sheets of paper or other like articles to a printing press, or folding machine, or for any other purpose. In carrying out my invention, I provide means for 25 supporting a plurality of sheets superimposed one upon another, preferably in a vertically disposed pile, although the sheets need not necessarily be fed from a pile, but 30 may be delivered in small quantities upon the feeding table, in any desired way.

Where the sheets are fed from a pile, as 35 in the present instance, suitable mechanism will be employed as shown, to feed the support or table upwardly as the sheets are removed therefrom. At one end of the supporting means or table I provide what I term delivering means, and mechanism is provided for combing or fanning out the 40 sheets so as to feed the topmost sheet into position to be gripped or seized by the sheet delivery mechanism, and delivered from the machine to a printing press, folding device, or other apparatus, for example.

45 In order to secure the accurate separation of the sheets, and also to prevent more than one sheet being withdrawn by the sheet delivery mechanism, I provide a controlling device for positively stopping the fanning 50 or combing of the topmost sheet when in proper relation to be engaged by the sheet delivery mechanism, and my improved controlling device operates in conjunction with the rear marginal portion of the topmost 55 sheet, so that it is brought into operation when the rear edge of the topmost sheet

arrives at a predetermined position. In the specific embodiment of my invention herein shown and described, the combing mechanism is normally held out of operative relation with the sheets by a spring or its equivalent, and at the proper moment in the cycle of the apparatus, after the delivery of a sheet, the combing mechanism is depressed into operative engagement with 60 the topmost sheet and the comber elevating mechanism is locked so as to allow the comber to remain in operative engagement with the topmost sheet. A presser foot rests upon the topmost sheet and is provided 65 with a suction aperture adjacent thereto, and normally out of contact with the sheet, and so located that as the presser foot passes off of the rear edge of the topmost sheet, marginal portions of the sheet adjacent to 70 said edge will be drawn against the suction aperture, by the suction therethrough, so as to close said aperture. The suction line connecting said suction aperture with the air exhausting device is provided with a branch 75 line leading to a pneumatic releasing device for the locking mechanism controlling the combing mechanism, the parts being so arranged that the releasing device will not be actuated as long as the suction aperture of 80 the presser foot is open, but the instant it is closed by the marginal portion of the top sheet, the suction will actuate the pneumatic releasing device, and withdraw the 85 locking mechanism, and permit the combing mechanism to be elevated out of operative relation with the sheet. At about the same time I prefer to exert a downward pressure 90 on the presser foot which rests upon the sheet beneath the topmost sheet, thus holding the lower sheets while the topmost sheet 95 is withdrawn and delivered.

Referring to the accompanying drawings, Figure 1 represents a side elevation of a sheet feeding machine containing one embodiment of my invention which I have selected for purposes of illustration.

Fig. 2 is a similar view of the opposite side of the machine.

Fig. 3 is a top plan view of the machine. 105

Fig. 4 is a central vertical longitudinal section of the machine.

Fig. 5 is a detail view of the presser foot and mechanism for supporting and actuating the same.

Fig. 6 is a partial rear elevation of the apparatus illustrated in Fig. 5.

Fig. 7 is a detail perspective view illustrating the construction and arrangement of the presser feet, two of which are shown arranged transversely of the machine, and 5 connected for joint operation.

In the machine shown in the accompanying drawings, 1—1 represent the side frames of the machine. 2 represents the supporting means or table for supporting the sheets to 10 be fed, in this instance a pile of sheets, indicated at 3, being shown. The table is supported by vertically movable rack bars 4, engaged by pinions 5 on a shaft 6 mounted in the side frames and provided at one end 15 with a ratchet wheel 7 engaged by a locking pawl 8, and also by an actuating pawl 9 pivoted to a short arm 10, secured to a rock shaft 11, extending across the machine, whereby, as hereinafter explained, the table 20 will be gradually raised as the sheets are fed and delivered therefrom, but as this feeding mechanism has no bearing upon my present invention, it is not specifically claimed herein, and any other suitable form of feeding 25 mechanism for feeding the table in case the sheets are fed from a pile may be employed, or the sheets may be placed upon or delivered upon the table in any other desired way.

30 The rock shaft 11 carries the "comber" 12 for fanning or combing out the upper sheet of the pile, and this comber consists in this instance of a rotary disk provided with a circular series of idle rollers, indicated at 35 13, the peripheries of which are adapted to engage the topmost sheet. The comber is supported on a shaft 14 carried at the outer end of a frame 15 adjustably secured to the rock shaft 11, as by set screws 11^a. Rotary 40 motion is imparted to the comber in any suitable manner, for example as herein shown, by means of a sprocket chain 16 passing around the sprocket wheel 17 on the comber shaft, and around the driving 45 sprocket 18 on the driving shaft 20, which is provided with any suitable means, as the driving wheel or pulley 19, for operating it from a motor, line shaft, or other suitable source of power. The comber is provided 50 with means for normally holding it out of contact with the paper and for depressing it into operative relation therewith. In this instance a depressing arm 23 is pivoted at its rear end to a cross shaft or support 24, 55 and is provided at its upper end with a link 25 having a slotted portion 25^a engaging a pin 23^a in the upper end of the depressing arm, the lower end of the link 25 being connected to the frame 15 carrying 60 the comber. The depressing arm 23 is provided with a friction roller 22 engaging a cam 21 on the shaft 20. A lifting spring, indicated at 100, is connected to the depressing arm 23 and to a fixed bracket 101 connected with the main frame and serves to

normally elevate the combing mechanism out of operative contact with the paper. The comber is depressed into operative contact with the paper positively by the cam 21, the slot 25^a permitting the comber to rest, by 70 gravity, upon the paper, and accommodate variations in the level of the paper. As soon as the comber is depressed into engagement with the paper, the depressing arm is locked by a pawl 26 on a shaft 27, which engages 75 a projection 28 carried by the depressing arm 23, so as to lock the parts and hold the comber in operative relation with the paper until the pawl or locking mechanism is released. The shaft 27, which carries the 80 pawl 26, is in this instance provided at one side of the machine (see Fig. 2) with a depending arm 95 provided with a retracting spring 98, which holds the locking pawl in operative position. I have shown, in Fig. 2, 85 a pneumatic releasing device for releasing the locking mechanism, which consists in this instance of a cylinder 102 provided with a piston 103, connected with a stem 104, for actuating the arm 95 in a direction against 90 the spring 98, to release the locking pawl 26 and permit the comber to be elevated by its lifting spring 100. The cylinder 102 is connected to a suction pipe 105, which in this instance is a branch pipe leading to a main 95 suction pipe 106 connected with a suction device 107 operated by a motor 108, or otherwise, for creating a suction in the pipe 106. The piston 103 of the pneumatic device may also be provided with a spring, indicated at 100 109, although this is not necessary, as the spring 98 would cause the piston to be retracted by the arm 95. Above the paper on the support or table, and adjacent to the rear edge of the topmost sheet, I provide 105 a presser foot, and as it is necessary and desirable that the machine shall feed sheets of different length and width, it is necessary that the presser foot shall be adjustable longitudinally of the machine with respect 110 to the sheet delivery apparatus hereinafter referred to. In the embodiment of my invention herein shown the side frames of the machine are provided adjacent to their rear ends each with a bracket 30 carrying a horizontally disposed guide rod 31, and upon these guide rods is supported a transverse rock-shaft 32 mounted in guides 33, sliding upon guide rods 31. Upon the rock shaft 32 is mounted a block 34 carrying a horizontally 115 disposed plate 35, which I term the presser foot. This plate 35 is so connected with the block 34 as to have a slight play, and is held by a spring 36 so as to have a yielding engagement with the topmost sheet, the construction, however, being such that by 120 rocking the shaft 32 forwardly, the block 34 will exert a positive downward pressure on the presser foot 35 which would be transmitted to the paper, as hereinafter described. 125 130

Extending slightly forward of, and slightly above the lower edge of the presser foot, is a suction device 37 provided with a suction aperture 38 in its lower face, the said 5 suction device being in this instance carried by a tubular part 39 secured to the block 34 and connected to the air pipe 106 before mentioned, so that a constant current of air is drawn by suction into the aperture 38. 10 For the purpose of slightly rocking the shaft 32, the said shaft is provided at one end, for example, with an arm 40, the upper end of which is pivotally connected to a sliding block 41 mounted on a horizontal rod 15 or link 42, to which it is adjustably connected by a screw 43, the said rod or link being pivotally connected at 44 to an arm 45, carrying a friction roller 46 at its upper end, engaging a cam 47 on a shaft of the 20 machine, in this instance, the driving shaft 20, the arm 45 being provided with a spring 48 for holding the roller 46 in engagement with the cam 47.

The operation of this portion of my invention is as follows. The machine is adjusted so that the presser foot 35 will pass off of the rear edge of a paper sheet at the exact instant that the sheet reaches the position in which it is to be engaged by the sheet 25 delivering means and delivered from the machine. The presser foot can be adjusted longitudinally of the machine, by sliding the blocks 33 on the guide 31, and securing them in adjusted position, and the presser 30 foot can also be adjusted transversely of the machine on the shaft 32 and locked in the desired position by a set screw, for example, indicated at 49. In some instances two or 35 more of these presser feet can be employed, and in Fig. 7 I have illustrated two of these 40 devices. It being understood that the presser foot lightly engages the topmost sheet under the pressure of the spring 36, and that the comber has been depressed and locked in 45 operative position, the rotation of the comber, which is continuous, will feed the topmost sheet along until the edge of the paper passes from under the presser foot, as indicated in Figs. 5 and 7, for example, at which 50 instant the suction device 37 will draw the rear edge of the paper up and bring it into contact with the lower face of the suction device, so as to close the suction aperture 38 therein, thus stopping the inflow of air 55 to the suction apparatus. This causes a suction to be exerted through the branch pipe 105 to the pneumatic releasing device, and creates a partial vacuum in the cylinder 102, causing the piston 103 to move inwardly, 60 and thus release the locking mechanism for the comber, which is promptly elevated by the lifting spring 100, thus stopping the forward movement of the sheet. This construction enables me to positively position 65 each topmost sheet with its forward edge in exactly the right position to be grasped by the sheet delivering mechanism, as the sheets are of uniform length, and I control the position of the sheets by the position of the rear edges of the same. And further, as 70 soon as the presser foot slips off of the rear edge of the topmost sheet, thereby releasing the combing mechanism and stopping the advance of the sheet, the presser foot clamps the sheet or sheets below, and holds them 75 firmly while the topmost sheet is delivered from the machine, so as to prevent them from being disarranged by friction with the topmost sheet during its withdrawal.

Any preferred form of sheet delivery 80 mechanism may be employed, whether of the gripper or roller type, which will take the sheets successively as they are fed to a predetermined position, and deliver them from the machine and into position to be 85 printed, folded, or otherwise treated. In the present instance I have shown a sheet delivery mechanism of the roller type, which comprises a continuously operated feed roller 50 which acts in conjunction with a pair of 90 rider wheels 51 carried by links 52 pivoted on a transverse shaft 53, which is secured to the upper ends of arms 54, mounted on a rock shaft 55. The rock shaft 55 is provided with an arm 56 which is pivotally 95 connected to one end of a yoke bar, the other end of which is provided with a yoke or forked portion 58, having a guiding engagement with the main driving shaft 20, and provided with a friction roller 59, for en- 100 gaging the cam 60 on the shaft 20, for moving the rock shaft 55 in one direction, a spring 61 being provided connected at one end to the frame, and at the other end to the arm 56 for moving the rock shaft in the 105 opposite direction. The cam 60 is so constructed as to hold the rider wheels 51 forward of their operative position with respect to the feed roll 50, the operative position being indicated by the dotted line X in Fig. 110 4, for example, and this being the position to which the forward edge of the topmost sheet is to be fed. As soon as the sheet has been brought to the proper position to be engaged by the delivery mechanism, the cam 115 60 will permit the spring 61 to move the rider wheels rearwardly until they occupy the operative position with respect to the roller 50 and the sheet to be fed and delivered, the rider wheels pressing upon the 120 upper surface of the front edge of the sheet and clamping the sheet between them and the continuously operating feed roll, and rapidly delivering the sheet from the machine. As soon as the sheet begins to travel 125 forward under the influence of the sheet delivery mechanism, the rear end of the sheet will be withdrawn from the suction aperture 38, thus allowing air to enter the suction pipe 106, and relieve the branch pipe 130

105 from suction, which permits the piston of the releasing device to be retracted and restores the locking mechanism to normal position, so that as soon as the comber is
 5 depressed into engagement with the topmost sheet of those remaining upon the supporting means, the comber depressing arm will be locked in its downwardly position, and the operation of the machine will be re-
 10 peated.

It will be understood that each time the shaft 11 is oscillated by the movement of the comber into and out of operative position, the arm 10 and pawl 9 will be operated
 15 to effect the movement of the ratchet wheel 7 on the shaft 6 carrying the pinions 5 engaging the vertical rock bars 4 of the table or paper supporting means, thereby imparting an upward feeding movement to the
 20 table to compensate for the removal of sheets therefrom. I do not limit myself to this particular table adjusting mechanism, as any other suitable means can be employed where the sheets are to be fed from a pile,
 25 and as hereinbefore stated the table feeding mechanism is not an essential feature of my invention, as it is not necessary that the sheets be fed from a pile, as a plurality of sheets may be supplied to the table by hand
 30 in any other way in which case no feeding mechanism for the table would be required, as the slot 25^a in the lifting link 25 connected with the depressing arm will enable the apparatus to accommodate itself to considerable variation in the position of the topmost sheet acted upon.

It will also be understood that the means for moving the rider rolls of the sheet delivery mechanism into operative relation act
 40 in timed relation with the means for depressing the presser foot upon the lower sheets while the topmost sheet is being delivered, and in this instance, they are both operated from the main driving shaft, although this is not essential.

What I claim and desire to secure by Letters Patent is:—

1. In a machine for feeding sheets and like articles, the combination with a support for a plurality of sheets, sheet delivery means for delivering the sheets singly, located adjacent to one end of the sheet support, a vertically movable comber, means for actuating the comber in a direction to feed the topmost sheet toward the sheet delivery means, and into position to be engaged by the sheet delivery means, means for elevating the comber out of operative relation with the sheets on said support, controlling means for said comber elevating means, having a part located adjacent to the opposite end of the sheet support from the sheet delivery means, and adapted to be brought into operation when the end of the
 60 sheet farthest from the sheet delivery means

reaches a predetermined position under the actuation of the comber, the sheet delivery means moving the sheet in the same direction as the comber.

2. In a machine for feeding sheets and like articles the combination with a support for a plurality of sheets, sheet delivery means located adjacent to one end of said support, for delivering the sheets singly, a vertically movable comber, for engaging the topmost sheet, actuating means for said comber, for driving it in a direction to feed the engaged sheet toward the sheet delivery means, and into position to be engaged thereby, means for elevating the comber out of operative relation with the sheets, a sheet engaging part located adjacent to the opposite end of the said sheet support from the sheet delivery means, resting upon the sheets, adjacent to their rear edges, and so located as to pass off of the rear edge of the topmost sheet, when the latter is in position to be engaged by the sheet delivery means, and controlling means for the comber elevating means, including a part located slightly nearer to the sheet delivery means than said sheet engaging part, and adapted to be brought into operation when the rear edge of the topmost sheet passes from beneath the said sheet engaging part and permits the latter to engage the next sheet below, the sheet delivery means moving the sheet in the same direction as the comber.

3. In a machine for feeding sheets and like articles, the combination with a support for the sheets, sheet delivery means, and a comber for moving the topmost sheet into position to be engaged by the sheet delivery means, of means for moving the comber into and out of operative relation with the topmost sheet, a controlling mechanism for the comber having a sheet engaging part, for engaging the sheet to be fed adjacent to its rear edge, operative connections between the said part and the comber for insuring the movement of the comber to inoperative position, when and as the said sheet engaging part passes off of the rear edge of the topmost sheet, and means normally operative after the sheet engaging part has passed off of the rear edge of the topmost sheet for depressing said part into firm engagement with the sheets below.

4. In a machine for feeding sheets and like articles, the combination with a support for the sheets, sheet delivery means, and a comber for moving the topmost sheet into position to be engaged by the sheet delivery means, of means for moving the comber into and out of operative relation with the topmost sheet, a controlling mechanism for the comber having a sheet engaging part, for engaging the sheet to be fed adjacent to its rear edge, operative connections between the said part and the comber for insuring

- the movement of the comber to inoperative position, when and as the said sheet engaging part passes off of the rear edge of the topmost sheet, and means operated in timed relation with the sheet delivery means, and normally brought into operation, after said sheet engaging part has passed off of the rear edge of the topmost sheet, for depressing said part firmly upon the lower sheets. 5
5. In a machine for feeding sheets and like articles, the combination with a support for the sheets, sheet delivery means, and a comber for moving the topmost sheet into position to be engaged by said sheet delivery means, of means for moving the comber into and out of operative relation with the sheet to be fed, a pneumatic controlling device for insuring the movement of the comber to inoperative position, a sheet engaging part, for engaging the sheet to be fed adjacent to its rear edge, a part provided with a suction aperture located in advance of said sheet engaging part, and in position to be closed by marginal portions of the topmost sheet, a suction pipe connected with said pneumatic controlling device for operating the same, and branch pipe connecting said suction pipe with said suction aperture. 10
- 30 6. In a machine for feeding sheets and like articles, the combination with a support for the sheets, sheet delivery means, and a comber for moving the topmost sheet into position to be engaged by said sheet delivery means, of means for moving the comber into and out of operative relation with the sheet to be fed, a pneumatic controlling device for insuring the movement of the comber to inoperative position, a sheet engaging part, for engaging the sheet to be fed adjacent to its rear edge, a part provided with a suction aperture located in advance of said sheet engaging part, and in position to be closed by marginal portions of the topmost sheet, a suction pipe connected with said pneumatic controlling device for operating the same, a branch pipe connecting said suction pipe with said suction aperture, and means for normally positively depressing said sheet engaging device upon the lower sheets when the said sheet engaging part has passed off of the rear end of the topmost sheet. 15
7. In a machine for feeding sheets and like articles, the combination with a support for the sheets, sheet delivery means, and a comber for moving the topmost sheet into position to be engaged by said sheet delivery means, of yielding means normally tending to hold the comber out of contact with the sheets, means for depressing the comber into engagement with the topmost sheet, locking means for holding the comber in operative position, releasing means for 20
- device, for engaging the topmost sheet adjacent to its rear edge and operatively connected with said releasing means for actuating the latter when and as said sheet engaging device passes off of the rear edge of the sheet. 70
8. In a machine for feeding sheets and like articles, the combination with a support for the sheets, sheet delivery means, and a comber for moving the topmost sheet into position to be engaged by said sheet delivery means, of yielding means normally tending to hold the comber out of contact with the sheets, means for depressing the comber into engagement with the topmost sheet, locking means for holding the comber in operative position, releasing means for 75
- said locking means, a sheet engaging device for engaging the topmost sheet adjacent to its rear edge, and so located as to pass off of the said edge when the sheet is in position to be engaged by the sheet delivery means, and operative connections between said sheet engaging device and said releasing means. 80
9. In a machine for feeding sheets and like articles, the combination with a support for sheets, sheet delivery means, and a comber for moving the topmost sheet into position to be engaged by said sheet delivery means, of yielding means normally tending to hold the comber out of contact with the sheets, means for depressing the comber into engagement with the topmost sheet, locking means for holding the comber in operative position, pneumatic releasing means for said locking means, a sheet engaging device for engaging the topmost sheet adjacent to its rear edge, and provided with a part having a suction aperture, in 85
- advance of the sheet engaging part and in position to be closed by a marginal portion of the sheet, and a suction pipe connected with said pneumatic releasing means, and said suction aperture. 90
10. In a machine for feeding sheets and like articles, the combination with a support for sheets, sheet delivery means, and a comber for moving the topmost sheet into position to be engaged by said sheet delivery means, of yielding means normally tending to hold the comber out of contact with the sheets, means for depressing the comber into 95
- engagement with the topmost sheet, locking means for holding the comber in operative position, pneumatic releasing means for said locking means, a movable presser foot provided with a sheet engaging part for engaging the topmost sheet adjacent to its rear edge, and so positioned that it will 100
- pass off of the rear edge of the sheet when the sheet is in position to be engaged by the sheet delivery means, said presser foot being provided with a part in advance of its sheet engaging means, having a suction aperture 105
- 110
- 115
- 120
- 125
- 130

adapted to be closed by a marginal portion of the sheet, suction means operatively connected to said pneumatic releasing means, and said suction aperture, and means for 5 positively actuating said presser foot to clamp it upon the sheets below the topmost sheet.

11. In a machine for feeding sheets and like articles, the combination with a support 10 port for sheets, sheet delivery means, and a comber for moving the topmost sheet into position to be engaged by said sheet delivery means, of yielding means normally tending to hold the comber out of contact with the 15 sheets, means for depressing the comber into engagement with the topmost sheet, locking means for holding the comber in operative position, pneumatic releasing means for said locking means, a movable presser foot provided with a sheet engaging part for engaging 20 the topmost sheet adjacent to its rear edge, and so positioned that it will pass off of the rear edge of the sheet when the sheet is in position to be engaged by the sheet 25 delivery means, said presser foot being provided with a part in advance of its sheet engaging means, having a suction aperture adapted to be closed by a marginal portion of the sheet, suction means operatively connected 30 to said pneumatic releasing means and said suction aperture, means for positively actuating said presser foot to clamp it upon the sheets below the topmost sheet, means for adjusting the presser foot longitudinally 35 of the machine to accommodate sheets of different length, and adjustable connections between the presser foot and the means for depressing the same to accommodate changes in the position of the 40 presser foot.

12. In a machine for feeding sheets and like articles, the combination with a support for the sheets, sheet delivery means comprising a continuously operating feeding 45 roll and superimposed rider rolls supported thereon, and normally held out of operative position, a comber for moving the topmost sheet into position to be engaged by said sheet delivery means, means for moving 50 the comber into and out of operative relation with the sheet to be fed, a controlling mechanism for the comber having a part for engaging the sheet to be fed adjacent to its rear edge, connections between 55 said part and the comber for insuring the movement of the comber to inoperative position when said part passes off of the rear edge of the topmost sheet, means for moving the rider rolls into operative position, to 60 deliver the topmost sheet, and means operating the timed relation therewith for de-

pressing said sheet engaging part upon the lower sheets after it passes off of the topmost sheet.

13. In a machine for feeding sheets and like articles, the combination with a support for the sheets, sheet delivery means, and a comber for moving the topmost sheet into position to be engaged by said sheet delivery means, yielding means normally tending to hold the comber out of operative position, a pivoted depressing arm operatively connected with the comber, a cam for actuating said depressing arm, a presser foot having a part for engaging the topmost sheet adjacent to its rear edge, and having a part in advance of the sheet engaging part provided with a suction aperture, a locking device for holding the comber in operative position, a pneumatic releasing device for the locking device, and suction means connected with said pneumatic releasing device and said suction aperture. 75 80

14. In a machine for feeding sheets and like articles, the combination with a support for the sheets, a sheet delivery device adjacent to one end of the support for acting upon the forward edges of the sheets to deliver them singly from the machine, means for advancing the sheets, movable into and out of operative relation with the topmost sheet on said support, and controlling mechanism for said sheet advancing means, including a sheet engaging device having a part for engaging the topmost sheet adjacent to its rear edge, and operative connections extending to said sheet advancing means and normally brought into operation when said sheet engaging device passes off of the rear edge of the topmost sheet. 90 95 100

15. In a machine for feeding sheets and like articles, the combination with a support for the sheets, sheet delivery mechanism adjacent to one end of said support for engaging the forward edges of the sheets, and delivering them singly, sheet advancing mechanism movable into and out of operative relation with the topmost sheet, controlling mechanism for said sheet advancing mechanism comprising a pneumatic device, and a presser foot having a sheet engaging part so located as to pass off of the rear edge of the topmost sheet, when the forward edge of the sheet is in position to be engaged by the sheet delivery means, and having a suction device provided with a suction aperture in advance of the sheet engaging portion and slightly above the same, and a suction pipe connected to said pneumatic device and to said suction aperture. 105 110 115 120

In testimony whereof I affix my signature.
ROBERT E. KEMPER.
